UNITED STATES PATENT OFFICE

CHARLES SCHELL, OF CINCINNATI, OHIO, ASSIGNOR TO SCHELL LEATHER GOODS COMPANY, OF CINCINNATI, OHIO, A FIRM COMPOSED OF CHARLES SCHELL AND ALBERT M. SCHELL

DESIGN FOR A BRIEF CASE

Application filed February 17, 1930. Serial No. 34,579. Term of patent 7 years.

To all whom it may concern:

Be it known that I, CHARLES SCHELL, a citizen of the United States of America, and a resident of Cincinnati, in the county of Hamilton and State of Ohio, have invented a new, original, and ornamental Design for a Brief Case, of which the following is a specification, reference being made to the accompanying drawing, forming part thereof.

The figure is a front elevational view of a brief case showing my new design.

The back of the brief case is plain.

I claim:

The ornamental design for a brief case as shown and described.

CHARLES SCHELL.
